UNITED STATES PATENT OFFICE

SARAH A. KELCHNER, OF NEW YORK, N. Y.

ASPARAGUS CAN

Application filed June 19, 1930. Serial No. 462,190.

This invention relates to cans adapted to contain bunches of asparagus, and the object of the invention is to construct such cans in such a way that the consumer will necessarily open the can not at the top thereof, but at the bottom, where the butt or cut ends of the asparagus are located.

In asparagus cans as heretofore made, a label illustrative of the contents is ordinarily applied, so that the consumer handles the can with the tips of the asparagus always extending upwardly into the free space at the top of the can. The tips of the asparagus are the delicate portions of this vegetable. 10 The ordinary housewife, accustomed to handle such cans in this way, almost automatically removes the top of the can in opening it and then the asparagus, in sliding from the can on to a plate or dish, is generally injured, notwithstanding care that may be taken in effecting the transfer of the contents of the can to the plate. If, on the other hand, the can is opened at the bottom, the asparagus slides from the can with its tougher 15 ends first and the tips are protected from injury because they are not exposed to violent contact with the receptacle to which they are transferred. The particular object of the present invention accordingly is to make up 20 the can in such a way that the consumer will be positively deterred from attempting to open the can at the top but will be compelled, by reason of some means associated with the can itself, to open it at its bottom and to 25 refrain from opening it at its top.

The manner in which this is accomplished, is shown in the annexed drawings in which Fig. 1 is a side view of a can of asparagus embodying my invention in one of its forms; 30 Fig. 2 shows a top view of such a can embodying a modification of my invention; and Fig. 3 shows a top view of another modification; Fig. 4 shows a view of the bottom of the can adapted to be used in conjunction 35 with each of the modifications of the invention shown in Figs. 1, 2 and 3.

In Fig. 1 the can illustrated comprises the top plate 1, sides 2 and bottom plate 3. The bunches of asparagus rest upon the bottom 40 plate with their cut or butt ends in contact

therewith. The bottom plate 3 is fabricated of such material or is so associated with the sides 2 of the can as to be readily removable by the manipulation of an auxiliary tool such as perforation by a can opener. Upon the can are contained prominent means for unmistakably and forcibly directing the consumer's attention to the necessity of opening the can at the bottom and not at the top. In Fig. 1 these means comprise the letters 4 and 45 symbols 5 printed upon the label or embossed on the sides of the can and preferably colored red or some other brilliant, contrasting color, the letters forming a legend such as "Open at the bottom" or "Open at this end" or one or more of such legends. The symbols 5 may also be of a similar connotation and as illustrated in Fig. 1 may be in the form of pointers or arrows. In Fig. 2 the top of the can is provided with a label reading, for example, in a prominent fashion: "Don't open this end". In Fig. 3, the legend is shown as embossed or stamped into the top of the can itself so that even if all the labels were removed, the consumer would still be properly advised. Such stamping or embossing of the top of the can obviously deforms the metal of this part of the can, and for that very reason, because its permanence represents the preferred embodiment of the invention. It is obvious that numerous modifications may be made without departing from the spirit of the invention and that the invention may be incorporated in a can adapted to contain asparagus in many other 50 forms and ways than those specifically illustrated which are intended to be merely illustrative or typical.

I am aware that cans of fruit and vegetables have probably been heretofore opened either at the top or at the bottom or have been so constructed that they might be opened at either end, but in all those cases it is immaterial whether the can is opened at one end or the other. It is only in the case of a vegetable such as asparagus which differs in delicacy of structure and tenderness in each of the vegetable units, that it makes any difference whether one or the other end of the can is 55 opened for the removal of its contents, and it 60

is only in connection with vegetables of this character that I claim the necessity of the presence of prominent, unmistakable means on the can to deter the consumer from opening the top of the can.

5 I claim:

1. A food package comprising a can substantially filled with a plurality of stalks of asparagus compactly arranged therein, said can having a substantially flat end wall adjacent which the butts of the stalks are arranged, the can further bearing indicia directing the consumer to open the can at said flat end wall, the side walls of said can being arranged so as to permit the stalks of asparagus to pass through the opening provided by removal of the flat end wall.
- 10 2. A can for asparagus having side walls, a substantially flat bottom end, and an opposite end comprising the top of the can when said can is in normal position of rest, there being indicia inscribed on the can defining the top and bottom ends respectively, and a plurality of substantially compactly packed stalks of asparagus in said can arranged longitudinally thereof with their butt ends adjacent the bottom end and their tender tip ends adjacent the top end, said bottom end supporting the stalks of asparagus on their butt ends
- 15 30 when the container is in normal position of rest and being of such a character as to be removable by operation of an auxiliary tool, said can further having indicia inscribed thereon directing the consumer to open the can at its bottom end, the walls of said can being so arranged as to permit the stalks of asparagus to pass through the bottom end when opened, whereby said asparagus stalks normally rest on their butt ends in the can and are removed from said can with their butt ends foremost thereby to effect protection of the tender tips.
- 35 40 45 3. A can for asparagus as claimed in claim 2 wherein the indicia for directing the consumer to open the can at its bottom end comprises a deformation of the top end of the can into an instructive legend.

In testimony whereof I have hereunto set my hand.

50 SARAH A. KELCHNER.
